E. VON EISENBARTH

Des. 109,630

TEXTILE FABRIC

Filed April 6, 1938

INVENTOR

Eduard von Eisenbath

UNITED STATES PATENT OFFICE

109,630

DESIGN FOR A TEXTILE FABRIC

Edith von Eisenbath, New York, N. Y.

Application April 6, 1938, Serial No. 76,321

Term of patent 3½ years

To all whom it may concern:

Be it known that I, Edith von Eisenbath, a citizen of the United States of America, residing in New York city, in the Borough of Manhattan, county and State of New York, have invented a new, original, and ornamental Design for a Textile Fabric, of which the following is a specification, reference being had to the accompanying drawing, forming part thereof, wherein, the figure is a plan view of a piece of textile fabric showing my new design.

I claim:

The ornamental design for a textile fabric, substantially as shown.

EDITH von EISENBARTH.
